UNDERFEED RETORT, INCLUDING RING
CONSTRUCTED TUYÈRE MEANS

Philip C. Malmsten, Milwaukee, Wis., assignor to
A. O. Smith Corporation, Milwaukee, Wis., a
corporation of New York

Application March 6, 1947, Serial No. 732,821

4 Claims. (Cl. 110—45)

1

This invention relates to a stoker retort assembly and is particularly directed to the construction of the tuyère portion of the assembly.

One object of the invention is to provide a retort assembly in which the tuyère portion has an improved service life without "burning out" or breaking.

Another object of the invention is to provide the tuyère portion of the retort assembly with maximum air opening permissible for ordinary coal, affording maximum efficiency of the blower unit.

Another object is to provide a tuyère construction in which generally high grade alloy metal is employed affording longer life and heat resistant qualities and reducing costs of replacements.

Another object is to provide the tuyère portion of the retort assembly of a plurality of tuyère members stamped from plate metal.

A further object is to provide the retort assembly with tuyere members of plate metal which are individually replaceable.

These and other objects and advantages of the invention will appear hereafter from the following description of an embodiment of the invention illustrated in the accompanying drawings.

In the drawings:

Figure 1 is a top plan view of the retort assembly with parts broken away and sectioned;

Fig. 2 is a longitudinal vertical section taken on line 2—2 of Fig. 1;

Fig. 3 is a fragmentary section taken on line 3—3 of Fig. 1; and

Fig. 4 is a fragmentary section taken on line 4—4 of Fig. 1.

The retort assembly of the invention comprises in general the retort elbow 1 partially encircled by the wind box 2 which is radially spaced from the elbow to form an air chamber therebetween and provided with a flanged rim 3 to support the tuyère section 4.

Wind box 2 is constructed of sheet metal formed and welded into a circular wall into one side of which extend the coal duct 5 and the air duct 6. The coal duct 5 connects with elbow 1 to supply coal to the burner from underneath by means of the feed screw 7 operated therein by suitable driving means, not shown. The air duct 6 supplies air under forced draft from a source, not shown, to wind box 2 for flow to tuyère section 4 to aid in the combustion of the fuel being burned.

The circular flange 3 extends horizontally outwardly a substantial distance from the upper portion of retort elbow 1 to the wall of wind box 2 and the outer end of the flange is welded to the wind box to close off the top of the same. Cir-

2

cumferentially spaced openings 9 are provided in flange 3 for flow to tuyère section 4 of the air supplied to wind box 2 by air duct 6.

The bonnet 10 of tuyère section 4 has a circular outer wall which is supported within annular groove 11 in flange 3 of wind box 2 and an inwardly turned flange 12 extending horizontally from the upper end of the outer wall and surrounding a central opening into the firebox of the unit. The joint between bonnet 10 and flange 3 is sealed by a suitable gasket or cement. Bonnet 10 is secured to flange 8 of retort elbow 1 by bolts 13 which extend diagonally downwardly through the bonnet and are threaded into flange 8. The heads of bolts 13 when in place are inset in bonnet 10 within suitable recesses 14 provided on opposite sides of the bonnet to protect the bolt heads in service.

The firebox of tuyère section 4 which is assembled within bonnet 10 has a plurality of generally flat plate metal disk-like members 15 with a central opening therethrough in line with the bonnet opening. Members 15 are vertically spaced by a plurality of rivets or tieing members 16 to provide the horizontal tuyère openings 17 therebetween for flow of the air received by the bonnet into the burner portion of tuyère section 4.

The lowermost tuyère member 15 is spot welded to the flanged upper end of the tuyère spout portion 18 of the firebox which is supported within annular groove 19 in the upper portion of retort elbow 1. Spout 18 is inwardly spaced from the circular wall of bonnet 10 to provide a substantial air chamber therebetween. The joint between spout 18 and elbow 1 is sealed by a suitable gasket or cement.

The uppermost tuyère member 15 is separated into halves to avoid the wall of bonnet 10 at recesses 14.

The spacing rivets 16 have longitudinally spaced flattened portions which fit into complementary slots 20 in the outer edge of each tuyère member and to form the rivet with vertically spaced shoulders 21 to support the plate members 15 thereon in vertically spaced position. The head 22 of each rivet engages the underside of the lowermost tuyère member 15 and the upper end of the rivets are riveted over within the holes provided in recess 14 in bonnet 10 to receive the rivets. By spot welding the lowermost tuyère member to tuyère spout 18, when the rivets are in place the entire retort assembly structure is secured together.

Spout 18 is of conical shape to carry out the taper of elbow 1. The outer diameter of members 15 is substantially the same but the inner diameter of the rings decreases from the top ring

to the bottom ring to carry out the taper of retort elbow 1 and spout 18 and provide the burner portion of the retort assembly of generally conical shape. The opening through flange 12 of bonnet 10 also cooperates to provide the firebox with a conical central opening.

The inner edge 23 of each member 15 is flared upwardly and into the horizontal opening 17 between the lower tuyère member and the adjacent tuyère member above to deflect the air upwardly which flows into the burner pot. Inner edge 24 of the bonnet 10 is similarly flared except at recesses 14 to similarly deflect the inflowing air. The tuyère members 15 are free of engagement with each other to prevent any substantial restriction of air flow between the tuyère members when air is flowing into the unit through air duct 6.

The retort shown has the horizontal tuyère openings 17 extending about the circumference of the burner without a break except for interruption by the walls of recesses 14 so that a uniform supply of air is provided from all sides as the coal moves upwardly through the central burner space of the retort.

The shape of inner edge 23 of tuyère members 15 and edge 24 of bonnet 10 prevents undue coal deposit and eventual clogging of the burner by providing a clear path for expansion of the body of coal as it gradually moves upwardly past tuyère members 15. In addition the location of the deflecting edges within the tuyère openings and spaced from the next above adjacent tuyère member does unduly obstruct the tuyère openings and provides for a maximum draft through the tuyère openings 17 and deflection of the same upwardly.

There are three tuyère members 15 shown in the drawings but the number may be varied depending on the size of firebox desired in the burner. The outer edges of the two lowermost tuyère members 15 are provided with suitable slots for the passage of bolts 13 for securing the bonnet to flange 8 of retort elbow 1.

The bonnet 10 may be provided with a plurality of openings 25 spaced about the circumference thereof to supply air to any coal which may fall over the top of the bonnet.

The tuyère members 15 are fabricated from heat resistant alloy plate stock and are readily pressed to shape. The manner of construction of the tuyères of the invention is an improvement over cast or like tuyères where difficult casting problems are involved to provide suitable tuyère openings. The assembly of the retort is likewise rapid and less costly and the individual tuyère members may be replaced.

Various embodiments of the invention may be employed within the scope of the accompanying claims.

I claim:

1. In a retort assembly for stokers having a top central firebox supplied with coal from beneath and a surrounding housing having a chamber for supplying air to the firebox through tuyères, a tuyère construction comprising a plurality of continuous plate metal ring members spaced vertically apart and disposed as the upper portion of the side walls of the firebox with the space between said plate members being substantially uniform and continuous circumferentially of the retort assembly to provide an equalized supply of air from all sides from the chamber in said housing, upwardly bared edges provided on the inner circumference of said plate

members and projecting within the tuyère openings and removed from the lower plate member and the next above adjacent plate member to deflect inflowing air and coal upward without substantial restriction of the tuyère openings, a plurality of tieing members extending through the outer end portions of the plate members to secure the plate members together, and means on said tieing member vertically spacing said plate members in fixed spaced relation.

2. In a retort assembly for stokers having a top central firebox supplied with coal from beneath and a surrounding housing having a chamber for supplying air to the firebox through tuyères, a tuyère construction comprising a plurality of continuous plate metal ring members stacked one above the other and disposed as the upper portion of the side walls of the firebox, means securing the lowermost plate member to the lower portion of the wall of the firebox, a plurality of tieing members extending through slots in said plates and securing the same to the wind duct and lower portion of the firebox, and shoulders provided on said tieing members to uniformly space the plate members vertically apart around the circumference of the firebox to provide an equalized supply of air to the firebox from all sides.

3. In a retort assembly for stokers having an open top central firebox supplied with coal from beneath and a surrounding housing having a chamber for supplying air to the firebox through a tuyère section, a tuyère construction comprising a plurality of substantially continuous plate metal members each having a central opening and spaced vertically apart and disposed as the upper portion of the side walls of the firebox with the vertical space between said plate members being substantially uniform and continuous circumferentially of the firebox, and combined spacing and securing means extending through the outer portions of said rings to secure and space the rings at their outer ends.

4. In a retort assembly for stokers having an open top central firebox supplied with coal from beneath and a surrounding housing having a chamber for supplying air to the firebox through a tuyère section, a tuyère construction comprising a plurality of continuous plate metal members each having a central opening and constructed of high heat resistant alloy pressed metal stock and spaced vertically apart and disposed as the upper portion of the side walls of the firebox with the space between said plate members being substantially uniform vertically and continuous circumferentially of the firebox, and combined spacing and securing means extending through the outer portion of said rings to secure and space the rings at their outer ends.

PHILIP C. MALMSTEN.
